UNITED STATES PATENT OFFICE

EDWARD M. TAYLOR, OF WORCESTER, MASSACHUSETTS, ASSIGNOR TO THE HEALD MACHINE COMPANY, OF WORCESTER, MASSACHUSETTS, A CORPORATION OF MASSACHUSETTS

GRINDING MACHINE

Application filed September 17, 1927. Serial No. 220,248.

The invention relates to grinding machines, and particularly to automatic grinding machines in which the grinding operation automatically terminates or ceases 5 when the workpiece has been brought to a predetermined size. More especially, the invention relates to grinding machines providing automatic means for separating the work and wheel for a dressing operation in 10 advance of attainment by the workpiece of the aforesaid predetermined size. A grinding machine of the above character has great utility when employed to grind the internal surfaces of small articles, such as gears, bushings, ball races and the like, and it is in connection with such a machine that the present invention is illustrated and described.

A machine of the above character provides means for causing a traversing movement between the grinding wheel and the workpieces, means to extend or amplify this traverse in order to cause the grinding wheel to move past a dressing instrumentality, followed by a resumption of the normal traverse to finish the grinding operation, and, 25 finally, means to cause a final substantial separation of the wheel and workpiece in order that the finished workpiece may be removed from the machine and an unground 30 one substituted in its place in the work holding chuck. Such a machine is shown in the co-pending application Serial No. 4466, of Heald, Guild, Burns and Garno, filed January 24, 1925 U. S. Letters Patent No. 1,751, 35 202, granted March 18, 1930.

During the dressing of the grinding wheel, as above outlined, it is desirable that the relative motion between the grinding wheel and the dressing instrumentality be at a slow rate 40 of speed, in order that grooves may not be cut in the surface of the wheel. During the final and finishing cuts on the workpiece, it is desirable that the speed of traverse be slower than it is during the preliminary or 45 roughing cuts, but it need not be so slow as it is during the dressing operation. On the other hand, the final movement of withdrawal can be, and desirably should be, at the greatest speed of which the machine is 50 capable, and the initial movement of the

grinding wheel or the work to bring one into engagement with the other can be at the same high speed.

Thus a grinding machine of the character set forth should have instrumentalities for causing the table or carriage which carries either the grinding wheel or work holding chuck, to be capable of at least four changes of speed in the cycle of operations on each workpiece. Such a grinding machine is 55 illustrated in a copending application Serial No. 25,900, of Heald and Guild, filed April 25, 1925 U. S. Letters Patent No. 1,779,094, granted Oct. 21, 1930. The present invention is, in one of its aspects an improvement 60 on the grinding machine shown in this application, in that it provides improved means for controlling the flow of pressure fluid which gives the wheel or work holding carriage its motions at different speeds. But 70 it is to be understood that the present invention is not limited to use in a grinding machine as above set forth, for the speed controlling instrumentalities could be used, for example, in a grinding machine which provides no dressing instrumentalities, but in 75 which it is sometimes desirable to slow down the speed of traverse at the final stage of grinding, as determined, for instance, by the reduction of the rate of cross or transverse feed that causes the grinding wheel to progressively cut deeper and deeper into the workpiece.

In another aspect the present invention is 80 an improvement upon the machine shown in my own copending application Serial No. 83,592, filed January 25, 1926, now Patent No. 1,682,673, granted August 28, 1928, in 85 that it is shown applied to a machine having the instrumentalities therein disclosed. Briefly, my former invention contemplated 90 the dressing of the grinding wheel in response to an electric circuit closed by action of the transverse feeding instrumentalities, and a subsequent known advance of the said 95 transverse feed to bring the work to the finished size, automatic compensating instrumentalities being provided to insure contact between the wheel and the dressing point, despite the ordinary wear due to the grind- 100

ing operation, and the reduction of the wheel due to the previous dressing. In this particular aspect of the present invention, improvements in the automatic electric switch-
5 ing mechanism are involved.

The present invention also involves the elimination of certain mechanical table controlling instrumentalities that were shown in the Heald, Guild, Burns and Garno application, and speed control instrumentalities shown in the Heald and Guild application, and the substitution of simpler instrumentalities; this improvement being made possible by reason of the novel valve employed,
10 which obviates the necessity of controlling the flow of fluid at the different stages of the grinding operation directly from the motion of the table, or from the action of the dressing mechanism in bringing the dresser point into position. According to the present invention, a single control device performs these functions, with the consequent elimination of many parts from the grinding machine carriage and a simplification of the
20 dresser-moving instrumentalities.
25

The invention further consists in the novel valve device per se, and in certain combinations of parts and motions, all of which will more fully appear in the following detailed
30 description, taken in connection with the accompanying drawings, in which—

Fig. 1 is a front elevation of a grinding machine constructed in accordance with the invention.

35 Fig. 2 is an isometric view of the automatically actuated valve mechanism that determines the speed of travel of the machine carriage, together with the actuating mechanism therefor and the electric switch mechanism which is incorporated with it.

Fig. 3 is a diagrammatic showing, in isometric form, of the various fluid pressure actuated mechanisms and the fluid pressure connections between them, without relation to
45 the actual positions of the parts in the machine.

Fig. 4 is a vertical sectional view of a certain portion of the mechanism shown in Fig. 2.

70

Fig. 13 is a wiring diagram.

Fig. 14 is a piping diagram in plan view, 75 showing the parts in substantially the position they occupy in the machine.

Like reference characters refer to like parts in the different figures.

Referring first to Fig. 1, an internal 80 grinding machine is shown having a reciprocating table or carriage 1, such as is ordinarily provided in any internal grinding machine. In such a machine, either the grinding wheel or the work to be ground may be carried on the table 1, the reciprocation of the latter being utilized in either case to produce a relative traversing movement between the grinding wheel and the work. As here shown, the table 1 supports and carries a 85 wheel head 2, while the work which is to be operated upon is held in a work head 3, the latter being carried by a bridge 4, which spans the slideways provided by the machine frame for the back and forth movement of 90 the table 1.

The grinding wheel 5 is carried on a spindle 6 which is suitably journaled in the wheel head 2, and any suitable means, which need not herein be described, is provided to 100 rotate said spindle 6 and wheel 5. The work-piece holding chuck, which is located inside the water guard 7, is also rotated, but desirably at a slower speed.

The reciprocation of the table 1 to cause 105 the rotating grinding wheel to make the required interior traverse of the rotating work-piece is imparted by means of fluid pressure controlling and reversing mechanism, desirably of the type described in United States 110 Letters Patent No. 1,582,468, to Heald and Guild, granted April 27, 1926. Irrespective, however, of the exact type of reversing mechanism employed, the fluid pressure mechanism procures the reversal of the table 115 1 at each end of the latter's normal working stroke by the use of spaced adjustable dogs 8 and 9, carried by the table 1 and adapted to alternately engage and move a reversing member 10. The latter, as clearly shown in Figs. 1 and 9, provides two upwardly extending portions 11 and 12 which are preferably of the same height, but are located in different vertical planes. The left hand table dog 8 is located in the plane of the right hand portion 11, and the right hand table dog 9 is in the plane of the portion 12; during the grinding operation, when the wheel 5 is moving back and forth within the workpiece, both portions 11 and 12 of the reversing
120

125 member 10 are caused to move in opposite directions, so as to alternately engage the dogs 8 and 9, and thereby move the table 110 back and forth. The reversing member 10 is provided with a central slot 13, through which the fluid pressure controlling mechanism passes, and which slot 130 is closed by a cover 14.

member 10 are situated adjacent the dogs 8 and 9 in position to be struck alternately by said dogs, and said member 10, by its consequent movements first in one way and then 5 the other, effects the reversals in the travel of the table 1.

The reason for providing spaced portions 11 and 12 in different planes on the reversing member 10, instead of merely forming it 10 with a single upwardly extending portion, as shown in the prior applications referred to, is to produce in the table 1 a traverse of very limited range, if desired. The traverse must always be great enough to move the reversing valve far enough to change the direction of flow of the fluid, but a greater 15 motion of the member 10, in response to a given movement of the table 1, is produced when the table dogs strike a part of the reversing member that is measurably offset 20 from the center line. This type of reversing member, however, is known to the art and need not be further described.

As already stated, the automatic operation 25 of the machine is controlled from the transverse feeding instrumentalities that feed the grinding wheel 5 in relation to the work-piece. These instrumentalities derive their motion from the motion of the table 1. 30 As shown in Fig. 1, a cam member 13 is adjustably fastened to a long bar 14 which in turn is anchored at one end to a stationary part of the machine, such as the bridge 4, the other end of said bar being a floating end, 35 but a roller 15 being provided by the table 1 to support this bar in any position of the table. The cam 13 is so positioned longitudinally of the bar 14 that a roller 16, carried by an arm 17 which is pivotally mounted 40 at 18 to a standard 19 extending upwardly from the table 1, engages said cam at the end of each inward stroke of the table 1. This results in an oscillation of the arm 17 for every stroke of the table, and such oscillations cause a pivotally mounted pawl 20 to 45 engage and move a ratchet gear 21. By a system of gearing fully described in my aforesaid copending application, which it is not necessary to describe herein, since it 50 forms no part of the present invention, movement of said ratchet wheel 21 is transmitted to a screw shaft 22.

The wheel head 2 is carried on a cross slide 55 which is mounted to travel on ways provided by the table 1, the line of movement of the cross slide being at right angles to the line of movement of the table 1. The screw shaft is journalled in bearings carried by the standard 19 that is attached to the table 1, and the 60 screw shaft engages a nut fastened to the said cross slide, so that angular movement of the screw shaft results in a feeding movement of the slide; this construction, being very old in grinding machines, is not illustrated 65 herein and any variations of the same or re-

versals of parts thereof can be employed without departing from the spirit of the present invention.

Connected to the ratchet wheel 21 is a hand wheel 23, a fragment of which is shown in Fig. 1, and by turning the ratchet wheel, the cross slide can be moved forward or backward by hand. In this connection, it should be noted that the pawl 20 engages the ratchet wheel 21 only when it is actuated, as it is 70 spring pressed outwardly, and is caused to move into engagement with the ratchet wheel by means of an adjustable cam device 24; from which it follows that the hand wheel can be freely turned at all times except when the roller 16 is in actual engagement with the cam 13.

Adjustably fastened to the hand wheel 23 or the ratchet wheel 21 is a cam member 25 which therefore moves angularly whenever these parts move. During the normal automatic operation of the machine, the cam member 25 successively engages an adjustable screw 26 carried by a lever 27 and a similar adjustable screw 28 carried by a lever 29. Rocking movement of the lever 27 is adapted to cause the normal working stroke of the table 1 to be amplified and to coincidentally bring a dressing device into position in the path of the extended movement of the grinding wheel. Rocking movement of the lever 29 is adapted to cause a final movement of the table 1 to separate the grinding wheel and the work head 3, the table being brought to a stop in the position shown in Fig. 1.

Referring to Fig. 13, the lever 27 carries a contact 30 which, when said lever is moved, engages a stationary contact 31, and the lever 29 carries a contact 32 which will similarly engage a stationary contact 33. The successive engagement of these pairs of contacts brings about the dressing operation and the final movement of separation aforesaid; the electromagnetic means and the mechanical means actuated thereby that causes such will be hereinafter described.

Referring now to Figs. 3, 12 and 14, so much of the reversing valve mechanism has been shown as is necessary to the understanding of the present invention. As shown in Fig. 14, fluid under pressure may be supplied from a pump 34 incorporated into the machine, or it may be supplied from any other suitable source. At all events, the fluid pressure supply line is indicated at 35 in the piping diagram of Fig. 14 and the diagrammatic view of Fig. 3, said supply line having a branch 36 that leads the fluid to the valve, generally indicated by the numeral 37, which controls the speed of flow of the fluid and thereby the speed of travel of the table 1. From the valve casing 37, piping 38 takes the pressure fluid to the reversing valve casing 39, which is shown in the sectional view of Fig. 12. As shown in said figure, the fluid 110

is admitted by way of a port 40 to a chamber 41, whence it is directed to one side or the other of a cylinder 42 (see Figs. 3 and 14), in which is located a piston 43, whose piston rod 43a is connected to the table 1. Ports 44 and 45 in the chamber connect by piping 46 and 47 to the opposite ends of the cylinder 42 and a reversing valve 48 directs the fluid by way of one or the other of said ports, the exhaust fluid escaping by way of the port 49. It will be understood of course that the reversing valve 48 is connected to the reversing member 10 so as to be actuated by it; the mode of this connection and the exact construction of the reversing valve 48, forming no part of the present invention, need not herein be described, particularly as it is shown in United States Letters Patent No. 1,582,468 granted April 27, 1926, to Heald and Guild.

Between the port 44 and the piping 46 is a valve 50 which is pressed downwardly towards its seat by means of a spring 51, but prevented from engaging said seat by reason of a slidable member 52 which engages a portion 53 projecting downwardly from said valve. With the parts in the position shown in Fig. 12, the fluid is flowing through the port 44 and past the valve 50, and consequently moving the table 1 to the right as the piping 46 connects to the left hand end of the cylinder. (In this connection it should be noted that the cylinder 42 is seen from the rear in Fig. 3, and the left hand end therefore appears to be the right hand end.)

When the table has moved to the right on its final stroke, having carried the grinding wheel well away from the workpiece, a pin 54a or other projection carried by the table on the underside thereof engages the top of a lever 54 and moves said lever in a clockwise direction. See Fig. 1 which shows the lever 54 having been moved. The action of the pin and lever is the same as that described in somewhat more detail in the patent to Heald and Guild, No. 1,582,468. According to the present invention, the lever 54 is connected to the sliding member 52 so that when the lever 54 is actuated by the final movement of the table 1, the sliding member is drawn to the left from the position shown in Fig. 12 to the position shown in Fig. 1. Thereupon a notch 55, provided in the surface of the sliding member, comes under the downwardly projecting portion 53 and allows the valve 50 to seat, which it does under the influence of the spring 51, and this action, as it stops the flow of fluid to the left hand end of the cylinder 42, stops the table. When, subsequently, after a new workpiece has been placed in the chuck provided by the workhead 3, the operator of the machine wishes to cause the table 1 to travel to the left to commence the grinding operation on this fresh workpiece, he swings a lever 56 provided on the front of the machine frame,

which lever is directly connected to the reversing valve 48 and swings it in the same angular direction. This action admits fluid under pressure to the right hand side of the cylinder and causes the table 1 to travel to the left Fig. 1, and the fluid can exhaust from the left hand end of the cylinder by reason of the fact that the valve can always be lifted by pressure applied underneath it. Once, however, the stop, not shown, carried by the table 1 has moved away from engagement with the lever 54, the latter swings back to the position shown in Fig. 12, carrying the slidable member 52 with it, these parts moving under the influence of a spring 57.

The movement of the sliding member 52, which as just described, occurs at the end and at the beginning of each separate grinding operation, is made use of to actuate the valve in the valve casing and also the electric switch or distributor mechanism that is associated with it. To that end the slidable member provides a pair of reduced portions 58 and 59 in its cylindric surface of otherwise constant diameter. The right hand end of the slidable member 52 therefore constitutes a slide valve, adapted to admit fluid under pressure, which is taken from a shunt passage 60 provided in the main reversing valve casting, to one or the other of two ports 61 and 62, depending on the position of the slide valve. In the position of parts illustrated in Fig. 12, which, as it will be remembered, is the normal position during the grinding operation, the reduced portion 58 connects the shunt passage 60 to the port 61 which carries the pressure fluid by way of piping 63 to the front of a cylinder 64 carried adjacent the valve casing 37. The opposite or rear end of said cylinder is connected by piping 65 to the port 62, and in the position of parts aforesaid, fluid can exhaust from port 62 by way of the reduced portion 59 to an exhaust port 66. A second exhaust port 67 is located on the other side of the port 61, and as the location of these four ports 61, 62, 66 and 67 is a symmetrical one, it follows that the port 67 is covered up when the slide valve is in the position shown in Fig. 12, as is clearly shown in said figure, while movement of the valve 52 to the left at the end of a grinding operation connects this port to the port 61 and covers up port 66, the fluid then being admitted to the rear of the cylinder 64 by way of the piping 65.

In the cylinder 64 is a piston 68 which has a piston rod 69 attached thereto. To the piston rod 69 is fastened a block 70 which provides a depending pin 71 fitting in a hole in a member 72 on the end of which is cut a segment of a spur gear. See Fig. 4. The member 72 is pivotally mounted on the casing 37 at 73, and its gear teeth engage the teeth of a spur gear 74 which is fastened to a shaft 75. The cylinder 64 is pivotally mounted at

76 to the casing 37, so that the piston rod 69 can move in a slight arc.

During the grinding operation on a work-piece and in fact at all times after the operator moves the lever 56 to the left to cause the grinding operation to be commenced, the shunt passage 60, that connects to the source of fluid under pressure, is connected by way of the port 61 and the piping 63 to the front end of the cylinder 64 and therefore is pulling on the piston 68 to tend to move the segment member 72 in a clockwise direction. This, of course, acts to tend to turn the gear 74 in a counterclockwise direction. But normally, except at certain intervals when an escapement mechanism that will be described is actuated, the gear 74 and the shaft 75 to which it is attached, cannot be moved, being held stationary by means of a pawl 77 which is part of said escapement and which engages with a ratchet 78 also fastened to the shaft 75. When, however, the pressure fluid is made active against the rear of the cylinder 64, by reason of movement of the slide valve member 52 as described, the gear segment member 72 is moved, rotating with it the gear 74 and the shaft 75, because there is nothing to prevent clockwise movement of the ratchet gear 78.

Referring to Figs. 1 and 9, the left hand table dog 8 is carried by a block 79 which, the same as the carrying block 80 of the dog 9 and the carrying block 81 of a dog 82 provided to reverse the travel of the table or carriage 1 at the end of its amplified dressing stroke, is adjustably secured to the table 1 by means of any suitable adjusting and holding devices, such for instance as the hand screw nuts 83, 83, 83 applied to all three blocks and engaging with a screw rack 84 carried by the table 1. The left hand normal reversing dog 8, however, and also the dog 82, instead of being fixed dogs, unmovable in relation to their holding blocks, as is the case with the right hand table dog 9, are pivotally mounted dogs, being pivotally secured to their respective carrying blocks 79 and 81 by means of pins 85 and 86, the striking ends of said dogs 82, 82, hanging downwardly by gravity and being held from further movement by the engagement of the upper parts of said dogs with the tops of guiding slots 87 and 88 in the blocks 79 and 81.

The block 79, besides carrying the reversing member 8, carries a cam member 89 that actuates the escapement mechanism referred to. As shown in the aforesaid figures, and also in Fig. 2, the cam member 89 is adapted to engage and depress a roller 90 which lies in its path, whenever the motion of the table 1 carries the cam past the roller. Said roller is carried by an arm 91 mounted on a shaft 92 which projects from the front of the machine frame, the arm 91 being mounted free

on said shaft, but normally connected to it by means of a pull pin 93 carried by a short arm 94 which is keyed to the shaft, the foregoing simply constituting a ready means for breaking the connection between the arm 91 and the shaft 92 in order to manually move the valve and switch mechanism, if desired. At all events, counterclockwise movement of the shaft 92, however produced, results in actuation of the escapement mechanism to allow the shaft 75 to be turned by the fluid pressure device, shown herein as a piston and cylinder, a definite angular amount.

Referring now to Figs. 2, 7 and 8, the shaft 92 has fastened thereto, inside the machine frame, a depending arm 95 that is connected, by means of a link 96, to a member 97, one end of which constitutes the pawl 77, hereinafter referred to. The member 97 is pivotally mounted on a stud 98 extending upwardly from the casing 37, and is normally pressed to cause the pawl portion 77 to engage the ratchet wheel 78 by means of a spring 99, which fits on a holding pin 100 carried by the casing 37, and is held in position in relation to the member 97 by means of a similar pin 101. Counterclockwise movement of the member 97 in response to actuation by the cam member 89 and the connecting mechanism just described, releases the ratchet wheel 78 so far as the pawl 77 is concerned, but the ratchet wheel 78 is prevented from moving a greater distance than the space between teeth by a second pawl 102 carried by a member 103, which is pivotally mounted on the same stud 98 that carries the member 97. A coil spring 104 surrounding the stud 98 and the hubs of the members 97 and 103 urges the member 103 in a counterclockwise direction, but until the member 97 moves, the member 103 cannot, by reason of the fact that they are kept separated a fixed angular distance by means, for example, of a short arm 103a fastened to the member 103 and engaging the side of the member 97. The above, of course, simply constitutes an escapement by means of which the shaft 75 is allowed to rotate a given angular distance when, and only when, the cam member 89 carried by the table 1 engages the roller 90.

Referring now to Figs. 5 and 6, the shaft 75 has secured thereto in any suitable manner a member 105, to which is attached a second member 106 by means of screws 107, 107. One or the other of these two members 105 and 106 is made of insulating material, and the second member is slightly movable with respect to the first, and is pressed outwardly by means of springs 108, 108 surrounding the screws 107, 107. To the member 106 is fastened, as by means of screws 109, 109, a contact member 110 which, in the different positions it assumes by reason of the intermittent rotation of the shaft 75, is adapted to

bridge the gap between terminals 111 and 112, or 113 and 114, or 115 and 116, located in a casing 117. In this manner the automatic inauguration, first of the dressing 5 stroke of the table 1, and subsequently of the final movement of withdrawal of said table, which occurs at the end of a grinding operation, when the workpiece has been brought to the desired size, is controlled.

10 Attached to the shaft 75, at a position below the contact member 110, is a rotatable member 118 located in the valve casing 37, but before describing this valve, the various operations in a complete cycle of the 15 grinding operation of the machine will be described, so that the purpose and function of this valve may be made clear.

The operator finds the grinding machine with its parts in the position shown in Fig. 20 1, which position may automatically assume at the end of each grinding operation. At this time, the contact member 110 is in the position shown in dotted lines in the wiring diagram of Fig. 13, by reason of the fact that 25 the slide valve member 52 is in its left hand position (Fig. 12) and fluid pressure is admitted to the rear of the cylinder 64, which has caused the shaft 75 to be turned to its extreme clockwise position and holds 30 it there. The operator, having placed an unground workpiece in the chuck, turned the hand wheel 23 back so that the grinding wheel can enter the hole in the workpiece, and properly set all adjustable parts of the 35 machine, moves the hand lever 56 to the left, which action moves the reversing valve 48 in a corresponding direction, and swings the reversing member 10 to the right. The table 1 immediately moves to the left for the 40 reasons already set forth, and this action releases the lever 54 and allows the sliding valve member 52 to move to the right under the influence of the spring 57. Thereupon the fluid pressure is made active at the front 45 end of the cylinder 64, tending to move the segment member 72 to the right and consequently the gear 74 and the shaft 75 in a counterclockwise direction. But none of these parts immediately move, for the reason 50 that the pawl 77 is engaging the ratchet wheel 78.

As the table 1 moves to the left, first the pivotally mounted dog 82, and subsequently the pivotally mounted dog 8 lift over the portion 55 11 of the reversing member 10 without effect on said reversing member; at some time intermediate these occurrences, the cam member 89 comes into contact with the roller 90 and depresses it momentarily. This action 60 causes the escapement mechanism, that has been described, to operate, and in consequence, the shaft 75 is turned a definite angular distance by the fluid pressure means.

The angular turning of the shaft is just 65 sufficient to move the contact member 110

into contact with the terminals 111 and 112 in the casing 117, so that the electric connections are in the condition shown in the wiring diagram of Fig. 13 in full lines. The machine proceeds to grind the workpiece in the usual manner, the travel of the table 1 being reversed at each end of its normal stroke by the dogs 8 and 9 acting on the portions 11 and 12 of the reversing member 10. When, however, the grinding operation has proceeded far enough so that the cam 25, carried by the hand wheel 23, has been moved by the automatic feeding occasioned by the cam 13 and roller 14 to engage the screw 27, the dressing operation takes place in the following manner.

As shown in the wiring diagram of Fig. 13, electric current is supplied from a generator G, or any other suitable source, and proceeds by way of a branching lead 119 to an electromagnet 120 which, as clearly shown in Fig. 1, is located on the front of the machine. The other terminal of the electromagnet 120 is connected by means of a conductor 121 to the contact terminal 112 in the casing 117. As the adjacent contact terminal 111 in said casing is at that time connected to the terminal 112 by means of the contact or bridging member 110, and as the terminal 111 is connected to the terminal 31 by means of a conductor 122, the electromagnet 120 is energized, it being understood that the levers 27 and 29 are grounded into the machine frame as indicated in the wiring diagram and that one terminal of the generator G is grounded into the machine frame by a ground wire 123, as is also indicated in said diagram. Referring now to Figs. 1 and 13, an armature 124 is located above the electromagnet 120 which, together with an upwardly extending arm 125 and a depending arm 126, all of which are conveniently made as one, are pivotally mounted on a stud or shaft 127 projecting from the front of the machine frame. The upper end of the arm 125 provides an upwardly inclined surface which normally lies in the path of, but beneath a pin 8a which projects forwardly from the left hand table dog 8; when, responsive to the energization of the electromagnet 120 as described, the armature 124 is drawn downwardly, the upwardly inclined portion of the arm 125 is projected into the path of the pin 8a and, as the table 1 moves to the right next following such energization, the pin 8a rides on the said inclined surface and is lifted clear of the portion 11 of the reversing member 10, and the table 1 continues its movement to the right unaffected by the dog 8.

Coincidentally with this action, and by 125 reason of the energization of the magnet 120, the depending arm 126 is moved to the right, thereby shifting a slide valve 128 to the right, which makes the pressure fluid active through branch piping 129 shunted into the main pip. 130

ing 35 to a cylinder 130, which contains a piston 131, the movement of the latter being adapted to lower a dressing device or diamond 132 into the path of movement of the grinding wheel 5. The fluid pressure connections and some of the parts for this operation are indicated diagrammatically in Figs. 3 and 14, and the diamond 132, which is mounted on an oscillatable carrying member 133 is shown in Fig. 1, but the details of its operating mechanism need not be further described herein, since they form no part of the present invention, being fully described in the copending application of Heald and Guild, Serial No. 25,900, filed April 25, 1925.

As the table 1 continues its movement to the right, carrying the rotating grinding wheel 5 out of the workpiece, the cam member 89, carried by the block 79, engages and 20 presses the roller 90 on the arm 91 and thus, by means of the escapement mechanism described, causes a second actuation of said mechanism, and this turns the shaft 75 far enough to carry the contact member 110 to a 25 position between the terminals 111 and 112 and the terminals 113 and 114. See Fig. 13. Subsequently, the wheel 5 contacts with the dressing diamond 132, which has been lowered into position as aforesaid, and is dressed and 30 trued thereby; thereupon the pivotally mounted dog 82 strikes the right hand portion 11 of the reversing member 10, and reverses the direction of travel of the table 1, said table carrying the grinding wheel 5 past the dressing device again and back into the workpiece. At the outermost limit of amplified travel of 35 the table 1, a cam member 134, which is in the same vertical plane as the upwardly extending arm 125, and which is carried by the block 81, engages said upwardly extending arm and returns it, and the armature member 124 and depending arm 126 to their initial position, thus moving the slide valve 128 to the left and relieving the diamond actuating cylinder 40 130 from the fluid pressure. Since the electromagnet 120 was deenergized when the shaft 75 was turned the second time, as just described, there is no danger of these parts moving again, and indeed, no further energization of the magnet 120 to cause dressing and truing of the wheel 5 can occur on this particular grinding operation. The return motion of the table 1 causes the diamond carrying member 133 to be raised to the position shown in Fig. 1, but the mechanism that performs this action forms no part of my invention.

The return motion of the table 1 also causes the cam member 89 to depress the roller 90, resulting in a third angular movement of the shaft 75, carrying the contact member 110 into engagement with the two terminals 113 and 114. The grinding wheel 5 now proceeds to take the final and finishing cuts on the 55 workpiece, the termination of this final stage

of the grinding operation being brought about by the engagement of the cam member 25 with the screw 28, responsive to actuations of the pawl 20 by the engagement of the cam 13 with the roller 16. When this occurs, the contacts 32 and 33 are brought together, causing energization of an electromagnet 135 located on the front of the machine frame directly behind the electromagnet 120.

Referring now to the wiring diagram of Fig. 13, this energization occurs in the following manner. The electric current proceeds by way of the branching lead 119 through said electromagnet 135, thence by 75 way of a conductor 136 and the left hand branch 136a thereof to the contact terminal 114; thence through the contact member 110 to terminal 113 and, by way of branch 137a and main conductor 137 to the terminal 33. 80 As this terminal is then engaged by the terminal 32, the current goes through the lever 29 to ground and, by way of the ground wire 123, to the generator G.

Energization of this electromagnet 135 90 attracts an armature member 138 located above the electromagnet and just behind the armature member 124 and which, together with an upwardly extending arm 139 to which it is attached, is pivotally mounted 95 on the same stud or shaft 127 on which the three members 124, 125 and 126 are mounted. The arm 139, as well as the arm 125, has an upwardly extending inclined surface and, as best shown in Fig. 9, this surface lies behind 100 the similar surface of the arm 125, and lies directly in the path of the two pivotally mounted dogs 8 and 82. Lifting of the arm 139, therefore, causes said dog 8 to be lifted above the right hand portion 11 of the reversing member 10 and the table 1 therefore proceeds to the right unaffected by said reversing dog, but it will be noted that during this phase of the cycle of the machine operation, the diamond carrying member 133 is 105 not moved. The table 1 continues to the right and the cam member 89, carried by the block 79, engages the roller 90 for the fourth time, thus moving the contact member 110 into engagement with the terminals 115 and 116. This movement of the contact member 110, however, does not de-energize the electromagnet 135, for the reason that a branch 136b of the conductor 136 is connected to the terminal 116, and a branch 137b of the conductor 137 is connected to the terminal 115; thus electric current proceeds by a similar path and the magnet remains energized and the arm 139 maintains its upward 115 position. For that reason, the pivotally mounted dog 82 also rides upwardly on the inclined portion of said arm 139, and is carried clear of the right hand portion 11 of the reversing member 10 and the table 1 continues to the right, where it is stopped by the 120 125 130 135 140

engagement of the stop 54a with the lever 54, in a manner similar to that shown and described in Patent No. 1,582,468 and described earlier in this specification. The machine 5 has now completed one cycle of operation and is in exactly the same condition as described at the commencement of this description of operation.

In a previous part of this description, it 10 has been related that the pressure fluid which gives the table 1 its reciprocatory motion, including the amplified movement of travel and the movement of withdrawal described, is taken from the main fluid supply line 35, by 15 way of a branch line 36, to the control valve 37 which determines the speed of travel of said table at any instant. Referring now to Figs. 10 and 11, this valve comprises a casing indicated by the aforesaid numeral 37, 20 which has a central vertical bore 140 therein, closed by a member 141 at the bottom, and by an overhanging portion 142 at the top, the latter having a small bore just large enough to permit the shaft 75 to pass therethrough. 25 The valve member 118, heretofore referred to is fastened to the bottom of the shaft 75 in any suitable manner and completely occupies the bore 140 except for a small space at the top in which is located a thrust bearing 143 adapted to take the upward thrust on the valve member and shaft, due to the pressure of the fluid. The valve member 118 has a vertical bore 144 which is closed at the top by the shaft 75, but the fluid, which enters the bore 144 by way of a channel 145 provided in the closure member 141, (said channel having a centrally located orifice which is therefore always in communication with the bore 144) can leave the bore 144 by way 30 of a port 146 in the side of the valve member 118.

Extending partly around the valve member 118, and at the level of the port 146, is a 40 quasi-annular passage 147 formed in the casing 37. Said passage 147 communicates with the piping 38 that leads to the table reversing valve 48, and it also communicates with the bore 144, by means of a plurality of ports, five in number in this embodiment of the invention and numbered 148, 149, 150, 151 and 152, respectively, in counterclockwise rotation. Obviously, however, the fluid can only flow through that one of these five ports which is in line with the port 146 in the valve 50 member 118.

Radially alined with the ports 148, 149, 150, 151 and 152 are a series of bores 148a, 149a, 150a, 151a and 152a. The first and last of these are made solely for the purpose of 60 drilling the ports 148 and 152, which otherwise could not very well be reached with a drill, and they are therefore threaded and provided with closing plugs of any suitable description. The bores 149a, 150a, and 151a, 65 however, are each provided with adjustable

screw threaded devices for regulating the amount of pressure fluid that flows through their corresponding ports 149, 150 and 151, respectively, and these devices, being all the same, will be described in connection with the 70 port 150, the regulating device for that port being shown in Fig. 10.

As shown in said figure, the bore 150a is closed with a screw threaded member 153, which itself is internally bored and threaded, 75 an adjustable screw plunger 154 fitting therein. The latter can be turned by means of the knob 155, and provides a closure portion 156 alined with the port 150, said closure portion advancing or receding from said port as 80 the plunger is turned. The effective opening through the port 150 can, by the above means, be varied with a great degree of accuracy. To make this device fluid tight, a packing 157 fits around the plunger 154 in 85 the bore 150a and may be compressed between the threaded member 153 and a washer 158.

From the foregoing description, bearing in mind the fact that the valve member 118 is attached to the shaft 75 and, therefore, must turn with it, it will be apparent that the speed of the grinding table or carriage 1 can be accurately regulated for all the various phases of the grinding operation described. Briefly, recapitulating, however, the valve member 118, at the commencement of a grinding operation, is in that position where the port 146 in said valve member is alined with the port 148 in the casing 37, and therefore, 90 the table 1, on its inward movement to carry the grinding wheel 5 into the hole in the workpiece, moves at its maximum rate of speed, unrestricted by the valve means of the present invention and limited only by the setting of a valve located in the reversing valve casing 39, which is controlled by a lever 159 on the front of the machine, this control being common in grinding machines of this class. To all intents and purposes, and so far 100 as the present invention is concerned, the table travels to the left at its full speed, until the cam member 89 engages the roller 90 and causes actuation of the shaft 75 as described; whereupon the valve member 118 is moved to 110 that angular position where the port 146 is in line with the port 149. At that time, or immediately subsequent to it, the grinding wheel 5 has entered the workpiece and the grinding operation has commenced. This 115 preliminary grinding operation to take the coarse cuts on the workpiece, with the table 1 travelling back and forth on a reciprocation of limited range, takes place at a speed determined by the setting of the adjustable screw 120 plunger 154 that controls the flow of liquid through the port 149 which may be anything within the limits of setting of said plunger, but ordinarily will be a fairly fast traverse, 125 in order that too much time may not be con- 130

sumed in getting the workpiece ground approximately to size.

When the workpiece has been ground approximately to size, the cam member 25, on the cross feed wheel 23, comes into contact with the adjustment screw 26 and the dressing operation is inaugurated as already set forth; just before contact between the grinding wheel and the diamond, the cam 89 again contacts with the roller 90, and the valve member 118 is, in consequence, moved a second time, bringing the movable port 146 in line with the port 150. When the wheel 5 contacts the diamond 132, therefore, both traveling outwardly and also as said wheel travels inwardly, the speed of reciprocation of the table 1 is determined by the setting of the adjustable screw plunger 154 that controls the effective opening through the port 150, which again can be anything within the limits of adjustability of said plunger, but in this case is preferably very slow, so that the diamond will not cut a groove in the grinding wheel, but on the contrary, will dress and true it to a perfect cylindrical surface.

As the table 1 travels inwardly after the dressing operation, the cam member 89 strikes the roller 90 for the third time, and the port 146 is shifted to that position where it lines up with the port 151. The setting of the adjustable screw plunger 154 that controls the passage of the fluid through this port 151 will vary somewhat according to the requirements of tolerance for the workpieces being ground, but generally it will be to cause the table to travel faster than it did during the dressing operation, but slower than during the preliminary grinding operation. At all events, the wheel now proceeds to take the final and finishing cuts on the workpiece until such time as the cam member 25 strikes the second adjustable screw 28, which signifies that the grinding operation is completed; whereupon the table 1 is caused to travel to the right to the position shown in Fig. 1, as already described, and the commencement of such action moves the valve member 118 a fourth time, bringing the port 146 opposite the port 152, so that the table moves to its position of rest at maximum speed, allowing the operator to remove the finished workpiece from the chuck at the earliest possible moment.

I claim,

1. In a grinding machine, the combination with a grinding wheel, work holding means, and a table or carriage carrying one of said parts, of fluid pressure means to reciprocate said table or carriage, a valve comprising a main port, a second main port, a further plurality of ports always connected to the first main port but not to the second, and a single movable member which in each position connects one and only one of said plurality of ports to the second main port, and means for

shifting said single movable member to cause the table or carriage to move at different speeds.

2. In a grinding machine, the combination with a grinding wheel, work holding means, and a table or carriage carrying one of said parts, of fluid pressure means to reciprocate said table or carriage, a valve comprising a main port, a second main port, a further plurality of ports always connected to the first main port but not to the second, and a single movable member which in each position connects one and only one of said plurality of ports to the second main port, and means controlled by said table or carriage to shift the position of said movable member.

3. In a grinding machine, the combination with a grinding wheel, work holding means, and a table or carriage carrying one of said parts, of fluid pressure means to reciprocate said table or carriage, a valve comprising a main port, a second main port, a further plurality of ports always connected to the first main port but not to the second, and a single movable member which in each position connects one and only one of said plurality of ports to the second main port, and escapement controlled means to actuate said single movable member to cause said table or carriage to move at varying speeds.

4. In a grinding machine, the combination with a grinding wheel, work holding means, and a table or carriage carrying one of said parts, of fluid pressure means to actuate said table or carriage, a valve comprising a main port, a second main port, a further plurality of ports always connected to the first main port but not to the second, and a single movable member which in each position connects one and only one of said plurality of ports to the second main port, escapement controlled means to actuate said single movable member, and means controlled by said table or carriage to actuate said escapement.

5. In a grinding machine, the combination with a grinding wheel, work holding means, and a table or carriage carrying one of said parts, of fluid pressure means to actuate said table or carriage, a valve comprising a main port a second main port a further plurality of ports always connected to the first main port but not to the second and a single movable member which in each position connects one and only one of said plurality of ports to the second main port, fluid pressure means to urge said movable member in one direction, escapement controlled means to allow said fluid pressure means to actuate said movable member to progressively cause said table or carriage to move at different rates of speed, and means to cause said fluid pressure means to urge said movable member in the opposite direction for the performance of a new cycle of grinding.

6. In apparatus as claimed in claim 1, the

combination with the parts therein specified, of adjustable means to adjust the flow of fluid through some of the plurality of ports.

7. In apparatus as claimed in claim 2, the combination with the parts therein specified, of adjustable means to adjust the flow of liquid through some of the plurality of ports.

8. In apparatus as claimed in claim 3, the combination with the parts therein specified, of adjustable means to adjust the flow of liquid through some of the plurality of ports.

9. In apparatus as claimed in claim 4, the combination with the parts therein specified, of adjustable means to adjust the flow of liquid through some of the plurality of ports.

10. In apparatus as claimed in claim 5, the combination with the parts therein specified, of adjustable means to adjust the flow of liquid through some of the plurality of ports.

11. In a grinding machine, the combination with a grinding wheel, means to cause said grinding wheel to take preliminary or roughing cuts on a workpiece, electromagnetic means to cause the cuts to be changed to the final and finishing cuts, and electromagnetic means to cause the grinding operation to be terminated, of a rotatable electric current distributor mechanism, a fluid pressure motor directly connected to said distributor mechanism to actuate it, and escapement operative means to allow said mechanism to be actuated.

12. In a grinding machine, the combination with a grinding wheel, means to cause said grinding wheel to take preliminary or roughing cuts on a workpiece, means to cause the cuts to be changed to the final or finishing cuts, and means to cause the grinding operation to be terminated, of a valve comprising a main port, a second main port, a further plurality of ports always connected to the first main port but not to the second, and a single movable member which in each position connects one and only one of said plurality of ports to the second main port, and escapement controlled means to operate said movable member to control the rate at which a workpiece is cut.

13. In a grinding machine, the combination with a grinding wheel, means to cause said grinding wheel to take preliminary or roughing cuts on a workpiece, electromagnetic means to cause the cuts to be changed to the final or finishing cuts, and electromagnetic means to cause the grinding operation to be terminated, of a rotatable valve to control the rate at which a workpiece is cut, escapement controlled means to operate said valve, and a distributor directly connected to the movable part of said valve to determine which phase of the grinding operation takes place.

14. In a grinding machine, the combination with a grinding wheel, work holding means, and a table or carriage carrying one of said

parts, of a reversing member to control the direction of travel of said table or carriage, a pair of adjustable table dogs to actuate said reversing member, one of said dogs being pivotally mounted and adapted to be lifted to allow it to pass said reversing member, a third adjustable dog, pivotally mounted and carried by said table or carriage beyond said first mentioned pivotally mounted dog, means interposable in the path of said first named pivotally mounted table dog to lift the same and allow the table to move beyond its normal working stroke, but to be reversed by the second pivotally mounted dog, and means interposable in the path of both of said dogs to allow the table to move beyond both of them.

15. In a grinding machine, the combination with a grinding wheel, a work holding device, a table or carriage carrying one of said parts, fluid pressure means to move said table or carriage, means to cause said fluid pressure means to operate said table or carriage through a limited reciprocatory traverse, work sizing mechanism, a dressing device, electromagnetic means to cause the traverse to be amplified, whereby to pass said wheel with said dresser, and electromagnetic means to cause the table to finally stop, said last two means being operated by said work sizing mechanism, of a single controlling device actuated between the several phases of the grinding operation as hereinbefore set forth and adapted to regulate the flow of the pressure fluid, whereby to obtain different carriage speeds during the different operations, said device also controlling the aforesaid electromagnetic means to prevent more than a given amount of wheel dressing and to cause resumption of the grinding thereafter.

16. In a grinding machine, the combination with a grinding wheel, a work holding device, a table or carriage carrying one of said parts, fluid pressure means to move said table or carriage, means to cause said fluid pressure means to operate said table or carriage through a limited reciprocatory traverse, work sizing mechanism, a dressing device, electromagnetic means to cause the traverse to be amplified, whereby to pass said wheel with said dresser, and electromagnetic means to cause the table to finally stop, said last two means being operated by said work sizing mechanism, of a rotatable valve and distributor device, and means to actuate it between the several phases of the grinding operation as hereinbefore set forth, whereby to regulate the flow of pressure fluid to obtain different carriage speeds during the different operations and to control the aforesaid electromagnetic means to prevent more than a given amount of wheel dressing and to cause resumption of the grinding thereafter.

17. In a grinding machine, the combination with a grinding wheel, a work holding device, a table or carriage carrying one of

said parts, fluid pressure means to move said table or carriage, means to cause said fluid pressure means to operate said table or carriage through a limited reciprocatory traverse, work sizing mechanism, a dressing device, electromagnetic means to cause the traverse to be amplified, whereby to pass said wheel with said dresser, and electromagnetic means to cause the table to finally stop, said 5 last two means being operated by said work sizing mechanism, of a single controlling device, and fluid pressure means to actuate it between the several phases of the grinding operation as hereinbefore set forth, said device 10 being adapted to regulate the flow of the pressure fluid, whereby to obtain different carriage speeds during the different operations, said device also controlling the aforesaid electromagnetic means to prevent more than a 15 given amount of wheel dressing and to cause 20 resumption of the grinding thereafter.

18. In a grinding machine, the combination with a grinding wheel, a work holding device, a table or carriage carrying one of 25 said parts, fluid pressure means to move said table or carriage, means to cause said fluid pressure means to operate said table or carriage through a limited reciprocatory traverse, and means to cause said table or carriage 30 to withdraw the wheel from the workpiece at the end of a grinding operation, of a valve controlling the flow of fluid and governing the speed of said carriage during different 35 phases of a grinding operation, escapement controlled means to operate said valve, a valve device to cause said table to stop upon the withdrawal of said carriage, and a fluid pressure motor to reset the escapement controlled valve, this fluid pressure motor being controlled by the last named valve device.

EDWARD M. TAYLOR.
